UNITED STATES PATENT OFFICE.

SAMUEL G. GOSS, OF CHICAGO, ILLINOIS, ASSIGNOR TO THE GOSS PRINTING PRESS COMPANY, OF SAME PLACE.

CASTING-BOX FOR STEREOTYPING.

SPECIFICATION forming part of Letters Patent No. 659,170, dated October 2, 1900.

Application filed March 16, 1898. Serial No. 674,068. (No model.)

To all whom it may concern:

Be it known that I, SAMUEL G. Goss, a citizen of the United States, residing in Chicago, in the county of Cook and State of Illinois, 5 have invented certain new and useful Improvements in Casting-Boxes for Stereotyping, of which the following is a specification.

My invention relates to casting-boxes for stereotyping, and has to do particularly with 10 the means for locking the core in the case, so that it is not apt to become displaced when the box is tilted to receive the type-metal.

To this end my invention consists, primarily, in providing a construction whereby the 15 core is automatically locked in the case by the operation of tilting the casting-box.

My invention also consists of certain other improvements, which will be specifically hereinafter pointed out.

20 What I regard as new will be set forth in claims.

In the accompanying drawings, Figure 1 is a side elevation. Fig. 2 is a plan view. Fig. 3 is a front elevation. Fig. 4 is a side elevation showing the casting-box in position for the cast, part being in section. Fig. 5 is a cross-section on line 5 5 of Fig. 1.

Generally speaking, the casting-box herein illustrated consists of a case trunnioned upon 25 a suitable support, so as to be adapted to tilt to a vertical position, and a core pivoted at one end to the case and adapted to be swung upon its pivot into the case to form the inner member of the mold and to be swung up out 30 of the way in order to permit of access to the case either for the purpose of inserting the matrix or for removing it. The case is provided with a series of clamps, which are adapted to turn down over the side edges of the core 35 when fitted in the case to clamp it in position, and the frame of the machine is provided with cams adapted to engage arms connected to the clamps, so that as the casting-box is swung upon its trunnions the clamps are automatically moved down upon the edges of the core 40 and tightly bind or lock it in position. A suitable counterbalance is provided, which is attached to the core and serves not only to assist in raising the casting-box to its elevated 45 position, but also to raise the core when unlocked from the case. The counterbalance

is so constructed that a part of its weight only is used after the core alone has been raised to a certain extent, so that the entire weight of the counterbalance operates to restrain 55 downward movement of the core.

Referring to the accompanying drawings for a more specific description of my improved casting-box, 6 7 indicate the side pieces of the frame of the machine, which 60 have at one end upwardly-extending arms 8 9, as shown in Figs. 1 and 3. The side frames 6 7 are connected by cross-bars 10 11 12 13, as shown in Figs. 1 and 3.

14 indicates the case of the casting-box, 65 which, as shown in Figs. 1 and 2, is provided with trunnions 15 16, mounted in suitable bearings 17 18 in the side frames 6 7. At the opposite sides of the rear end of the case 14 are lugs 19 20, as shown in Fig. 2, which lugs 70 are connected by a cross-bar 21. As shown in Fig. 1, the rear lower corners of the lugs 19 20 are squared to fit the squared sockets in arms 22 23, which are mounted upon the cross-bar 11, as shown in Fig. 3, and are 75 adapted to be rocked by the operation of a lever 24, connected with said cross-bar 11, as shown in Fig. 1. When the lever 24 is in the position shown in Figs. 1 and 2, the arms 22 23 serve to lock the case 14 in a horizontal position, and by raising the lever 24 the case 80 may be unlocked to permit of its being tilted to receive the cast.

25 26 indicate standards which rise from the cross-bar 10, as shown in Figs. 1 and 3, and 85 are adapted to support the front end of the case 14 when in its horizontal position, as shown in Fig. 1, said case being provided with short legs 27 28, which are adapted to rest upon the upper ends of the standards 25 90 26, as shown in Figs. 1 to 3.

29 indicates a stop which projects horizontally from the cross-bar 10 and serves to intercept the rear end of the case 14 when tilted, as shown in Fig. 4, said case being provided 95 with a pin 30, which is adapted to strike said stop, as shown.

31 32 indicate cams, which are secured to the inner faces of the side frames 8 9, as shown in Figs. 3 and 4, said cams in the construction herein shown being located a short distance back of the trunnioned bearings 17 100

18. The object of the cams 31 32 is to operate the clamps, as will be hereinafter described. The upper portions of the cams 31 32 are beveled, as shown at 33 in Fig. 3, so that the clamping operation will be gradual, as will be hereinafter set forth.

34 indicates a semicylindrical core which is adapted to fit into the case 14 to form the inner member of the mold in the usual way. 10 The core 34 is of slightly-less diameter than the internal diameter of the case, so as to provide space between them for the matrix and plate. At its rear end the core 34 is provided with arms 35 36, which are pivoted upon the 15 cross-bar 21, as shown in Fig. 2, so that the core may swing vertically about said rod 21. The core 34 is also provided with a cross-bar 37, which is arranged about midway of the length of the core and projects over the side 20 edges of the case, as shown in Fig. 2, thus serving to prevent the core from entering the case beyond a certain point. The forward end of the core 34 is beveled, as shown at 38 in Figs. 3 and 4, to form a funnel to facilitate 25 the pouring of the molten metal into the mold.

39 40 indicate clamps for locking the core in the case. The clamps 39 40 are mounted, respectively, upon shafts 41 42, said shafts being supported in bearings 43 44 at the side 30 edges of the case. 45 indicates collars upon the shafts 41 42 to prevent displacement. The clamps 39 40 are of such length and shape that when rocked in a proper direction by the rotation of the shafts 41 42 they will bear down 35 upon the side edges of the core 34, thereby locking the core in place. The shafts 41 42 are rocked to operate the clamps by the cams 31 32 through the instrumentality of arms 46 47, which project from collars 48 49, respectively mounted upon and keyed to the shafts 41 42. The arms 46 47 are provided at their ends with rollers 50 51, respectively, which are adapted to bear against the inner faces of the cams 31 32 when the casting-box is tilted. 45 As shown in Figs. 1 and 3, the rollers 50 51 are adjustably secured in slots 52 in the ends of arms 46 47, so that the pressure of the clamps may be adjusted.

53 indicates a cross-bar secured upon the 50 upper surface of the core 34, which also serves to limit the extent to which the core can move into the case.

54 indicates a shaft which is mounted in bearings 56 57, secured upon the upper surface of the core near its front end, as shown in Fig. 2. The shaft 54 carries at its ends cams 58 59, which are so located as to rest upon the side edges of the case when the core is in place, as shown in Figs. 1 and 2. Said 55 cams are so adjusted that by rocking the shaft 54 they will operate to raise the front end of the core to a small extent out of the case, and their function is to loosen the core after a cast has been made, so that it may be thrown up 60 out of the way. Lever 60 is provided for rocking the shaft 54.

61 62 indicate the usual sidesticks, which

are adapted to fit between the side edges of the case and core, as shown in Fig. 5. The rear ends of the sidesticks 61 62 are adapted 70 to fit into suitable sockets in the end ring 63, which closes the rear end of the mold. The end ring 63 is provided with slots 64, adapted to fit over pins 65, carried by the case, which pins serve to prevent the displacement of the 75 end ring and retain it in position when the core is thrown up out of the case, as shown by dotted lines in Fig. 1.

66 indicates a counterbalance, which consists of blocks 67 68, connected by rods 69, as 80 shown in Fig. 1. The rods 69 are fixedly secured in the lower block 67, and the block 68 is arranged to move vertically upon said rods. The heads 70 of the rods 69 prevent the upper block from becoming detached from them. 85

71 indicates a flexible connection connected to the block 68 at one end and at its other end to a staple 72, connected to the cross-bar 37 and carried by the core. The cord or flexible connection 71 runs over a pulley 73. 90

74 indicates a suitably-arranged support adapted to carry the lower block 67 when it is dropped to a certain point.

The operation of my improved casting-box is as follows: To prepare the box for a cast, 95 the core is unlocked from the case by turning the casting-box to its horizontal position, the unlocking being automatically effected by the movement of the rollers 50 51 out of operative contact with the cams 31 32 and the action of springs 75, which are connected to rearwardly-projecting arms 76, carried by the clamps and to the case, so that they serve to throw the clamps out of operative position as soon as the rollers 50 51 move out of operative contact with the cams. The lever 60 is then thrown over to the left, thereby raising the core slightly out of the case and permitting the sidesticks 61 62 to be removed. As soon as the core is disengaged from the case 100 it is raised to the position shown in dotted lines or higher, if desired, the counterbalance assisting in this movement of the core. During the first part of the upward movement of the core the entire weight of the 105 counterbalance is operative; but as soon as block 67 moves down to the support 74 it rests upon said support, leaving only the upper block 68 effective, said block then moving 110 down upon the rods 69, as indicated by dotted lines in Fig. 1. The matrix may then be placed in position in the case, after which the core is moved down into operative position and the casting-box tilted to the position shown in Fig. 4, the lever 24 being operated 115 to throw the arms 22 23 out of engagement with the lugs 19 20. As soon as the box commences to rock upon its trunnions the rollers 50 51 move into operative contact with the cams 31 32, thereby throwing the clamps 39 120 40 over and down upon the side edges of the core. The pressure is at first gradual, owing to the beveled faces of the cams 31 32, but is increased to the maximum early in the tilting.

125

130

135

movement or soon after the tilting commences. When the casting-box assumes the position shown in Fig. 4, the cast is made and the box returned to its horizontal position.

- 5 I have described in detail the construction of the casting-box herein shown; but I wish it to be understood that I do not restrict myself to the specific details of the construction shown and described, as various modifications 10 may be made without departing from my invention. For instance, the position of the cams and of the clamps may be varied and various other changes may be made without materially altering the operation of the machine.

15 That which I claim as my invention, and desire to secure by Letters Patent, is—

1. In a casting-box, the combination with a tilting case and a core, of mechanism adapted 20 to engage the core, and connections between said mechanism and case whereby when the casting-box is tilted said mechanism will be caused to press down upon the core, force said core into the case and hold it in place, substantially as described.

2. In a casting-box, the combination with a tilting case and a core, of clamps adapted to engage the core, and cam mechanism between 25 said clamps and case whereby when the casting-box is tilted said clamps will be caused to press down upon the core, force said core into the case and hold it in place, substantially as described.

3. In a casting-box, the combination with a 30 tilting case having rock-shafts at each side thereof, clamps carried by said rock-shafts, and cam mechanism for rocking said shafts when the casting-box is tilted, of a core adapted to fit into said case and to be locked into 40 position by said clamps, substantially as described.

4. In a casting-box, the combination with a 45 tilting case and a core, of clamps adapted to rock on axes substantially parallel with the sides of the case to engage the side edges of the core for locking the core in the case, means for automatically operating the clamps to lock the core when the casting-box is tilted, and means for automatically moving said 50 clamps out of operative engagement with said core, when the casting-box is returned to its normal position, substantially as described.

5. In a casting-box the combination with a 55 tilting case and a core, of clamps provided with means for automatically actuating them and locking the core in the case when the casting-box is tilted, and springs arranged in position to automatically move said clamps out of operative engagement with said core when 60 the casting-box is returned to its normal position, substantially as described.

6. In a casting-box, the combination with a supporting-frame, of a case pivotally mounted in said frame, stationary cams carried by said frame, a core adapted to fit into said case, clamps carried by said case and adapted to rock on axes substantially parallel with the case to engage the side edges of said core to lock it in operative position, and arms connected with said clamps and adapted to engage said cams for automatically operating said clamps when the casting-box is tilted, substantially as described.

7. In a casting-box, the combination with a 65 tilting case and a core, of clamps carried by said case and adapted to rock on axes substantially parallel with the case to engage the side edges of said core to lock it in operative position, and means for automatically operating said clamps when the casting-box is 70 tilted, the said means being constructed and arranged to impart an increasing pressure to said clamps, substantially as described.

8. In a casting-box, the combination with a 75 tilting case and a core, of clamps carried by said case and adapted to engage the side edges of said core to lock it in operative position, and cams for automatically operating said clamps when the casting-box is tilted, the said cams being provided with beveled 80 engaging portions, whereby a gradually-increasing pressure will be imparted to said clamps, substantially as described.

9. In a casting-box, the combination with a 85 stationary frame, and cams carried thereby, of a case pivoted upon said frame, the core for said case, rock-shafts carried by said case, clamps carried by said rock-shafts, arms for rocking said rock-shafts, and rollers carried by said arms adapted to engage said cams, 90 substantially as described.

10. In a casting-box, the combination with a 95 stationary frame, and cams carried thereby, of a case pivoted upon said frame, the core for said case, rock-shafts carried by said case, 100 clamps carried by said rock-shafts, arms for rocking said rock-shafts, and adjustably-mounted rollers carried by said arms, adapted to engage said cams, substantially as described.

11. In a casting-box, the combination with a 110 case and a core pivoted at one end thereto, of automatic mechanism adapted to engage the core, and connections between said mechanism and case whereby when said casting-box is tilted said mechanism will be caused to engage said core, force it into the case and hold it in place, substantially as described.

SAMUEL G. GOSS.
